[57] ABSTRACT

This invention relates to multi-stage rotary jacks, of the kind in which each stage has a vane that is capable of turning with respect to the wall of a cylindrical casing, the vane or the casing constituting, as desired, a rotor and a stator and all the stages being coaxially aligned one above the other.

According to the invention, the stator and rotor members of each stage are idly mounted on a central shaft except for one of said members of an end stage and this excepted end member is keyed to the central shaft to rotate therewith but the rotor of each stage is keyed to the stator of one of its two contiguous stages so as to rotate therewith.

8 Claims, 5 Drawing Figures

SHEET 1 OF 2

FIG. 1FIG. 3FIG. 2## MULTI-STAGE ROTARY JACKS

This application is a continuation of U.S. application Ser. No. 810,212 filed on Mar. 29, 1969 and now abandoned.

It is known that rotary jacks used at this time do not generally permit of rotations of less than 360° and do not possess the flexibility sufficient to satisfy the multifarious requirements of industry.

The present invention has for an object a rotary jack having multiple elements which removes or minimizes these drawbacks and, in particular, allows a limited rotation to be obtained but, nevertheless, which is as high as is desired. In certain other cases, which will become apparent in the description to follow, the invention allows several successive rotations to be obtained on the same member and having a predetermined value, the sum of these rotations being capable of exceeding 360°.

To this end, the invention has for an object a multi-stage rotary jack, each stage or elementary rotary jack comprising a vane that is capable of turning with reference to the wall of a cylindrical chamber, these two members indiscriminately constituting what can be referred to as the rotor and the stator of the element.

According to the invention, these stages are coaxially aligned one above the other and their members (stator and rotor) are idly mounted on a central shaft with the exception of one of the members (rotor or stator) of one end stage that is itself keyed on to rotate with the central shaft but, however, the rotor of each stage is keyed on to rotate with the stator of one of two contiguous stages.

In accordance with another feature, the central shaft has at least one supply channel leading into the interior of the chambers of each stage.

In order that the invention may be more clearly understood, reference will now be made to the accompanying drawings which show two embodiments thereof by way of example, and in which:

FIG. 1 shows an axial section through a four-stage rotary jack in accordance with the invention,

FIG. 2 shows a section along the line II—II of FIG. 1,
FIG. 3 shows a section along the line III—III of FIG.

1,
FIG. 4 shows a view similar to that of FIG. 1, of a modification of the invention; and

FIG. 5 shows a section along the line V—V of FIG. 4.

Referring now to the drawings, reference will first be made to FIGS. 1 and 2, in which can be seen a jack that comprises four identical stages or elements, designated by the general reference A,B,C and D. Each stage is constituted by a cylindrical casing 1 having in the interior thereof a sleeve 2 provided with a radial vane 2a which is mounted to rotate about the axis of the casing. An abutment 3 fixed to the casing 1 and extending up to the sleeve 2 limits the angular movement of displacement of the vane and defines with it two chambers 1a and 1b.

The vane and the casing respectively constitute the rotor and the stator of each stage in the embodiment herein described.

The sleeves 2 and the casings 1 of each stage are idly mounted on a central shaft 4 by means of roller bearings. The central shaft thus ensures a satisfactory alignment and centering of all the stages of the jack. The rotor 2, 2a of the upper end stage D is keyed on so as

to rotate with the shaft 4 by any desired means, but the casing 1 forming the stator of the lower end stage A is fixed to a block P constituting the lower end of this stator.

As shown, the sleeve 2 is connected to the shaft 4 through an intermediate rotatable member 21, which includes a downwardly extending finger 22 received in a recess 23 in sleeve 2. The shaft 4 is fastened to the rotatable member 21 by a suitable fastening means, such as screws 24. In operation, rotation of sleeve 2 causes an interior surface of recess 23 to engage the finger 22, whereby the rotatable member 21 is rotated by the sleeve 2, the rotatable member in turn rotating the shaft 4.

On the other hand, as will readily be apparent from FIG. 1, the rotor 2 of the stage A passes through the upper cover of the casing of this stage and has at its end a recess 2b cooperating with a spigot 1c provided on the inner surface of the casing 1 of the contiguous stage B. The same construction is employed for the other stages, each rotor thus being keyed to rotate on the stator of one of the two contiguous stages.

Two conduits 5 and 6 are provided in the casing 1 of the lower end stage A, said conduits leading respectively into the chambers 1a and 1b of this stage. These conduits are respectively adapted to be connected to a source of fluid under pressure and discharge piping.

Two conduits 7 and 8 are provided in the sleeves 2 of each stage and these conduits lead, on the one hand, into the chambers 1a, 1b and, on the other hand, into circular internal necks 9 and 10. For its part, the central shaft 4 is provided with two bores 11 and 12, the bore 11 having orifices 11a at the level of the necks 9 of each stage, whilst the bore 12 has orifices 12a at the level of the necks 10. The upper ends of the bores 11 and 12 are obturated in any desired fashion. Thus, all the chambers 1a are in communication by the intermediary of the bore 11, and the chambers 1b by the bore 12. The operation of the composite jack is thus as follows. It will be supposed that the initial position of all the vanes 2a of the stages correspond to that shown in FIG. 2, in which the vanes 2a do not touch the abutments 3.

When the conduit 5 is placed in communication with the source of fluid under pressure and the conduit 6 with the discharge piping, the fluid under pressure passes into the chamber 1a of the lower stage A effecting a rotation, in the direction of arrow F (FIG. 2), of the vanes 2a which drive back the fluid contained in the chamber 1b.

The pressure extant in the chamber of the lower stage A is transmitted to the chamber 1a of the upper stages B, C and D by conduits 7, necks 9 and the bore 11, effecting the rotation of their vanes 2a with reference to the corresponding casing 1.

However, with reference to the fixed casing 1 of the lower stage A, the rotations of the various vanes 2a add together, since each stator is keyed on the next adjacent lower rotor; the central shaft 4 keyed on the last rotor 2a turns with respect to the structure through an angle equal to the sum of the rotations of each vane with respect to its casing. There is thus obtained a total rotation of the shaft which is greater than 360° and, in the example described, equal to four times the maximum rotation of each stage.

It should be stressed that the explanations given above neglect the flow losses which can be produced in

the communications between the various stages. It is not certain that the vanes of the four stages turn simultaneously about the same angle; in any case, a predetermined rotation of the shaft 4 corresponds to each quantity of fluid introduced through the conduit 5.

The return to the initial position represented in FIG. 2 is effected by permuting the connections of the conduits 5 and 6.

FIGS. 4 and 5 show another embodiment of the invention, in which the members referred to above are not described again but have been given the same reference numerals augmented by 100.

In this embodiment, the central shaft 104 is fixed and the stator of the lower stage A₁, constituted by a sleeve 102, provided with two symmetrical radial vanes 102a, is also fixed by downwardly extending fingers 131 received in recesses 132 in base 133. Thus, the sleeve 102 is connected to the shaft 104 through the base 133. The rotor 101 carries two abutments 103 and is keyed on the lower stator of the next adjacent upper stage B, by a suitable keying means. As shown, keying is effected by fingers 141 on the inner surface of the stage B, which are received in and cooperate with corresponding recesses 142 in the rotor 101 of the stage A₁. In a similar fashion, the rotor of each of the other stages is keyed on the stator of the stage immediately thereabove and the rotor 101 of stage D₁ is keyed to wheel 113. At the upper part of the composite jack, the rotor, constituted by casing 101, is keyed to rotate on a toothed wheel 113 cooperating with a driving member that is not shown in the drawing. Each stage of the composite jack comprises two vanes and thus two chambers 101a and two chambers 101b are present. All the chambers 101b communicate via a bore 112 and necks 110 and are adapted to be successively connected to discharge piping and piping for fluid under pressure.

The bores 111a and 111b, etc. are, on the other hand, provided on the central shaft and respectively communicate by necks 109 with the chambers 101a of each stage.

These bores are adapted to be selectively connected to a source of fluid under pressure and to discharge piping.

It is to be observed that, in this embodiment, the various stages are not generally identical. More precisely, the abutments 103 have different relative dimensions, thus permitting different rotations of the rotors with reference to the corresponding stators. The operation is thus as follows: the rotors 101 are all in the position set out in FIG. 5 and one of the bores 111, for example, the bore 111b, is placed in communication with the source of fluid under pressure. The rotor 101 of the stage B₁ is displaced in the direction of the arrow F₁ until it comes to rest on the abutments 103 by diminution of the chambers 101b which drive back the fluid that they contain, into the bore 112. In its movement, the rotor 101 of the stage B₁ drives the stator of the stage C₁ which drives the corresponding rotor by the vanes resting on the abutments 103 and so on up to the rotor 101 of the upper end stage keyed on the toothed wheel 113. This latter thus turns about an angle equal to that of the rotor of the stage B₁.

The supply of the fluid under pressure from another stage causes the rotation of the toothed wheel to be added to the preceding one.

The return to the initial position may be effected in two fashions: firstly, if the group of the bores 111a,

111b, etc. are connected to the discharge piping whilst injecting the fluid under pressure by the bore 112, all the stages simultaneously take up the position shown in FIG. 5; secondly, in normal operation, the pressure in the bore 112 lies between the pressure of the source and that of a fluid reservoir and it is thus possible to obtain a return to the initial position, stage by stage. For this purpose, it is sufficient to connect the bore 111 of each stage to the reservoir.

Due to this construction, it will be found to be possible to cause a predetermined position of the toothed wheel 113 to correspond to each "state" of the group of stages, each stage possessing two "states" defined by the direction in which the rotor is stopped on its stator.

It will also be observed that in the case where the angular travel of one stage is insufficient, two or more stages may be coupled together in parallel in a manner similar to that described above with reference to FIGS. 1, 2 and 3.

When the multi-stage rotary jack is utilized for moving a heavy mass, it may be necessary to use shock absorbers to avoid shocks at the termination of the travel.

These shock absorbers may be of any desired kind, for example, utilizing springs or having resilient or pneumatic abutments.

Advantageously, they may have a construction identical to that of the jacks hereinabove described, interposed at any desired points of the chain, but permanently supplied in such a fashion that they shall be stopped in the direction opposite to the control. To this end, it is preferred to provide two shock absorbers having opposed actions.

If, for example, it be supposed that the stage B₁ is a shock-absorbing stage, its bore 111b may be permanently supplied, thus maintaining the abutments 103 touching the vanes 102a in the direction of the arrow F₁. Preferably, in this case, a counter-pressure, less than that of the supply pressure of the bore 111b, is maintained in the central channel 112, for example, by a discharge valve adjusted to a convenient value.

Such a stage B₁ thus constituted as a shock absorber, allows the shocks to be limited when the wheel 113 is moved in the direction opposite to that of arrow F₁. At the moment of shock, the abutments 103 can slightly elongate the vanes 102a whilst driving back the feed fluid into the bore 111b. Thus a certain energy due to the inertia of the members in movement may be dissipated by the alternate flows passing through the bores 111b and the bore 112 which are provided with discharge valves which are conveniently adjusted.

As has been indicated, it will be preferable to provide a second shock-absorbing stage analogous to that which has been described but its supplies are reversed in such a manner that, in the absence of shocks, the abutments 103 touch the vanes 102 in the direction opposite to that of the arrow F₁. The second shock-absorbing stage thus allows shocks to be avoided when the wheel 113 is driven in the direction of the arrow F₁.

It will be well understood that the invention may be applied to many fields and is not limited by the embodiments described and shown but, on the contrary, embraces all modifications thereof.

What is claimed is:

1. A rotary jack, comprising:

a shaft; and

a plurality of actuating stages, including two end stages and at least one intermediate stage posi-

- tioned coaxially around said shaft and aligned with each other, each stage comprising a casing and a sleeve within the casing, said casing including a rotational restraining means, said sleeve including a vane, the casing and the sleeve being mounted coaxially around said shaft for relative rotational movement with respect to each other, said vane and rotational restraining means cooperating with each other to limit the relative rotational movement of said casing and sleeve, one of said casing and sleeve defining a rotor and the other a stator, the rotor of one stage being drivingly connected to the stator of one of its contiguous stages, the stator and rotor of said at least one intermediate stage being idly mounted on said shaft and one of said rotor and said stator of one of the end stages being connected to the shaft.
2. A rotary jack as defined in claim 1 wherein the sleeve and casing of each stage define at least one chamber and said shaft has at least one conduit leading into the interior of said at least one chamber.

3. A rotary jack as defined in claim 2 wherein the shaft has as many conduits as there are independent stages, each conduit being associated with a chamber of at least one of said stages.
4. A rotary jack as defined in claim 1 wherein said shaft is fixedly mounted.
5. A rotary jack as defined in claim 1 wherein a chamber of at least one stage is a shock absorber and is permanently connected to a conduit for carrying fluid under pressure.
6. The rotary jack as defined in claim 1 wherein the casing of each stage is a rotor and the sleeve of each stage is a stator.
7. A rotary jack as defined in claim 1 wherein the casing of each stage is a stator and the sleeve of each stage is a rotor.
8. The rotary jack as defined in claim 1 wherein said shaft is rotatably mounted.

Reconsideration and allowance of this application are requested.
